DESIGN FOR A BROOCH OR SIMILAR ARTICLE

Alfeo Verrecchia, Providence, R. I.

Application December 6, 1945, Serial No. 124,410

Term of patent 3½ years

(Cl. D45—19)

To all whom it may concern:

Be it known that Alfeo Verrecchia, a citizen of the United States, residing at Providence, in the county of Providence and State of Rhode Island, has invented a new, original, and ornamental Design for a Brooch or Similar Article, of which the following is a specification, reference being had to the accompanying drawing, forming part thereof.

Fig. 1 is a plan view of a brooch embodying my new design.

Fig. 2 is a side elevation of a brooch embodying my new design, showing the pin thereof in dotted lines.

I claim:

The ornamental design for a brooch or similar article, substantially as shown.

ALFEO VERRECCHIA.
